CLAIM

The ornamental design for a pipe connector for furniture kits, as shown and described.

DESCRIPTION

FIG. 1 is a front perspective view of a pipe connector for furniture kits, showing my new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom view thereof;

FIG. 7 is a right side view thereof;

FIG. 8 is a left side view thereof;

FIG. 9 is a cross sectional view thereof, taken along the line 9-9 in FIG. 3;

FIG. 10 is a cross sectional view thereof, taken along the line 10-10 in FIG. 3; and,

FIG. 11 is a cross sectional view thereof, taken along the line 11-11 in FIG. 3.

The broken lines shown in FIGS. 9-11 are for environmental purposes only and form no part of the claimed design.

1 Claim, 10 Drawing Sheets
